(57) **CLAIM**

I claim the ornamental design for a remote control transmitter, as shown and described.

DESCRIPTION

FIG. 1 is a top perspective view of a remote control transmitter showing my new design;

FIG. 2 is a bottom perspective view thereof;

FIG. 3 is a top plan view thereof;

FIG. 4 is a bottom plan view thereof;

FIG. 5 is a left side elevation thereof;

FIG. 6 is a front elevation thereof; and,

FIG. 7 is a right side elevation thereof.
